(57) **CLAIM**

The ornamental design for a desk magnifier, as shown and described.

DESCRIPTION

FIG. 1 is a top, front, right side perspective view of an embodiment of a desk magnifier;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1; and,

FIG. 8 is a bottom cross-sectional view of FIG. 1 taken along line 8 of FIG. 2.

The evenly dashed broken lines show portions of the article that form no part of the claimed design. The unevenly dashed broken lines in FIG. 7 represent boundaries of the claimed design and form no part of the claimed design. The unevenly dashed broken lines in FIG. 2 represent the cross-sectional line of FIG. 8 and form no part of the claimed design.
